UNITED STATES PATENT OFFICE.

WILLIAM B. SMITH WHALEY, OF MALDEN, MASSACHUSETTS, ASSIGNOR TO AMERICAN WHALEY ENGINE COMPANY, OF BOSTON, MASSACHUSETTS, A CORPORATION OF MASSACHUSETTS.

INTERNAL-COMBUSTION ENGINE.

1,378,072.

Specification of Letters Patent.

Patented May 17, 1921.

Application filed January 27, 1917. Serial No. 144,970.

To all whom it may concern:

Be it known that I, WILLIAM B. SMITH WHALEY, a citizen of the United States, residing at Malden, in the county of Middlesex and State of Massachusetts, have invented a new and useful Improvement in Internal-Combustion Engines, of which the following is a specification.

My invention relates to operating gears for internal combustion engines, by means of which gears the engine may be manipulated and controlled so far as the operations of the valves and ignition apparatus coupled with the engine and operated by said gears are concerned, and is more particularly intended, but without limitation thereto, to be used in connection with internal combustion engines operating on my improved retarded combustion cycle described in my co-pending application entitled Internal combustion engines, filed December 21, 1916, Serial No. 138,207, which requires the use of an auxiliary valve, the office of which is to introduce and time the admission into the cylinder of compressed air for self-starting, combustion supporting, and stratifying purposes.

The object of this invention is to provide an operating gear for controlling and operating the valve or ignition mechanisms of internal combustion engines, or both, and is especially applicable in connection with said auxiliary valves employed in engines operating on my improved retarded combustion cycle above referred to, and may also be used to control and operate the ignition system for the engine as well, if desired, said operating gear being applicable to either reversing or non-reversing types of internal combustion engines and capable of providing variable features for affording flexibility to the working performance and manipulation of the engine.

It will be here noted that the accompanying five (5) sheets of drawings disclose but one specific embodiment of the invention, the same being coupled with the three-cylinder, self-starting and reversing vertical type of internal combustion engine operating on my above referred to improved retarded combustion cycle, but I do not wish to limit the invention thereto, since the same may be applicable with engines having one

or more cylinders, whether of the reversing or non-reversing types, horizontal or vertical, and whether operating on my improved retarded combustion cycle or not.

Referring to the accompanying five (5) sheets of drawings:

Figure 1 represents an elevational and diagrammatic view of a three-cylinder vertical reversing internal combustion engine embodying my invention, showing the same coupled with the auxiliary air-valves of the different cylinders of the engine and also with two independent ignition systems, namely, an igniter and a magneto system.

Fig. 2 represents an enlarged view of the indicator and circuit closing member of the operating-gear.

Fig. 3 represents a diagrammatic view of the magneto system as employed and shown in Fig. 1.

Fig. 4 represents a cross-sectional view taken on line 4—4 Fig. 1, looking in the direction of the arrows, showing the middle cylinder of the engine in section, with the piston operating therein in the head-dead-center position.

Fig. 5 represents an end view of an igniter shown in Fig. 1, showing the same partly sectioned with the operating member thereof engaged with the armature member and in the act of raising the same to the "spark-ing" position.

Fig. 6 represents a part view of Fig. 5 but shows the armature of the igniter disengaged from the operating member thereof and in the act of dropping to its normal position, during which return period the spark is generated.

Fig. 7 represents a part sectional view taken through the operating-gear, showing the same set in the "neutral" position which is the resting position of the engine.

Fig. 8 represents the same view as Fig. 7 but shows the gear set in the "full forward" running position, when the crank-shaft of the engine rotates in the direction of the arrow marked "F."

Fig. 9 represents the same view as Fig. 7 but shows the gear set in the "full reverse" position, when the crank-shaft of the engine rotates in the direction of the arrow marked "R."

Fig. 10 represents an enlarged view of the main air-valve mechanism of the operating-gear.

Fig. 11 represents a sectional view taken 5 on line 11—11 Fig. 7.

Fig. 12 represents a sectional view taken on line 12—12 Fig. 10 looking in the direction of the arrows.

Fig. 13 represents a sectional view taken 10 on line 13—13 Fig. 7 looking in the direction of the arrows.

Fig. 14 represents a sectional view taken on line 14—14 Fig. 7 looking in the direction of the arrows.

Fig. 15 represents a sectional view taken 15 on line 15—15 Fig. 7 looking in the direction of the arrows.

Fig. 16 represents a diagrammatic view showing the relative positions of the operating-gear-eccentrics, operating the auxiliary air-valve and the igniter mechanism, for the left end cylinder of the engine shown in Fig. 1, corresponding to the "neutral" setting of the operating-gear for that particular cylinder, when the piston and crank thereof are positioned as shown.

Fig. 17 represents a similar diagrammatic view to that shown in Fig. 16 but represents the middle cylinder of the engine and shows the "neutral" setting of the operating eccentrics for the auxiliary valve and igniter mechanisms thereof.

Fig. 18 represents a similar diagrammatic view to Figs. 16 and 17 but shows the "neutral" setting of the operating members for the right end cylinder of the engine shown in Fig. 1.

Fig. 19 represents a diagrammatic view similar to Fig. 16 but shows the operating-gear mechanism shifted to the "full forward" position which corresponds to the position of the operating-gear shown in Fig. 8.

Fig. 20 represents a similar view to Fig. 17 but shows the operating-gear mechanism shifted to the "full forward" position, corresponding to the setting of the operating-gear shown in Fig. 8.

Fig. 21 represents a similar view to Fig. 18 but shows the operating-gear mechanism shifted to "full forward" position, corresponding to the position of the operating-gear shown in Fig. 8.

Fig. 22 represents a similar view to Fig. 16 but shows the operating-gear mechanism shifted to the "full reverse" position, corresponding to the setting of the operating-gear shown in Fig. 9.

Fig. 23 represents a similar view to Fig. 17 but shows the operating-gear mechanism shifted to the "full reverse" position corresponding to the setting of the operating-gear shown in Fig. 9.

Fig. 24 represents a similar view to Fig. 18 but shows the operating-gear mechanism

shifted to "full reverse" position corresponding to the setting of the operating-gear shown in Fig. 9.

Fig. 25 represents the operating-gear end view of the engine shown in Fig. 1. 70

Fig. 26 represents a diagrammatic view of the setting of the crank-shaft of the engine, corresponding to the position assumed thereby, as shown in Figs. 1 and 25.

Fig. 26^a represents another of the possible 75 balancing positions of the crank-shaft of a three-cylinder engine.

Fig. 27 represents a similar view to Fig. 20, which represents the middle cylinder of the engine, but shows the operating gear 80 mechanism, when the engine is running "full forward," set at the closing position of the auxiliary air-valve, which, as is shown, occurs when the crank is but a few degrees away from the exhaust position of 85 the cylinder.

Fig. 28 represents a similar view to Fig. 27 but shows the engine running "full reverse," also showing the operating-gear 90 mechanism set to the closing position of the auxiliary air-valve which occurs just previous to the reaching of the exhaust position of the engine.

Fig. 29 represents a sectional view taken on lines 29—29 Figs. 4 and 25, looking in 95 the direction of the arrows.

Fig. 30 represents a sectional view taken on line 30—30 Fig. 29 looking in the direction of the arrows.

The terms employed herein are used in 100 the generic and descriptive sense, and therefore are not intended primarily as terms of limitation.

Like numerals refer to like parts throughout the several views of the drawings.

The numeral 1 represents an engine bed in the bearings of which the crank-shaft 2 operates, which shaft is provided with the cranks 3, 4 and 5 for the cylinders 6, 7 and 8, respectively, which are duplicate cylinders of the double-ended-valveless two-cycle type, as shown in Fig. 4, and within which operate the ported and skirted type of pistons 9, which are provided with the piston-rods 10 and are coupled with the cross-heads 11, or as is shown in Fig. 1 in the case of the left end cylinder, with the piston type of compressor cross-head 12, the latter operating in the air-compressing-cylinder 13 provided 110 therefor in the frame 14 which supports the cylinder 8 and which is secured to the engine bed 1 in any suitable manner, or made integral therewith, if desired. The cross-heads 11 operate in the cross-head-guides 15 provided 115 therefor in the frame-members 16. The cross-heads 11 and the compressor cross-head 12 of the cylinders 6, 7 and 8 are coupled with the cranks 3, 4 and 5 of the crank-shaft 2 by the connecting-rods 17, 18 120 125 130

and 19, respectively. 20 represents the exhaust-port of the cylinder, 21 a regulatable transfer valve, 22 the fuel-proportioning-valve which discharges into the intake manifold 23 and enters into the pre-compression end 24 of the cylinder through the ports 25.

The combustion ends 26 of the cylinders are provided each with the spark-plugs 27 which may be connected with the respective igniters of the cylinders, and other spark-plugs which may be connected with the magneto as shown in Fig. 3; and the automatic co-acting valves 29 which are slidably supported, as shown in the discharge member 30, which is open to and communicates with the receiving chamber 31 of the auxiliary valve member 32 within the bore 33 of which is preferably fitted the ported-sleeve-member 34. The latter is secured in position with said auxiliary valve casing 32 by means of the flange 35 which closes the lower end thereof, as shown in Fig. 30, while the upper end 36 is open to the compressed air-distributing-pipe 37. Within the ported-sleeve-member 34 operates the auxiliary reciprocating valve 38 which is perforated, as shown, to allow for balancing conditions of the valve, and is provided with the valve-stem 39 which preferably connects with the cross-head 40, as shown in Fig. 25, and which cross-head slidably operates on the guides 41 provided therefor.

42 represents an ordinary high tension igniter of the common type, as for example, the so-called "Wico igniter" which is adapted in its operation to magnetize and suddenly demagnetize one or more magnetic coils positioned within a permanent magnetic field, or in other words, to suddenly demagnetize the magnetic core of said coil as distinguished from the make and break and direct induction systems and devices and is operated by a reciprocating action,—it being here noted that my operating gear will perform with other types of igniters to equal advantage, as for example, with the so-called "Bosch igniter" which operates on an oscillating stroke instead of a reciprocating stroke, and which with but little modification may be coupled with the operating-gear herein shown to be operated thereby.

43 represents the slidable igniter operating bar which carries the pivoted latch 44 and engages in the up-stroke thereof by means of said latch 44 with the armature-bar 45, as shown in Fig. 5, and disengages therefrom when said latch 44 comes into contact with the timing-wedge 46, as shown in Fig. 6, when the armature of the igniter is allowed to drop and in so doing generates the current which causes the sparking of the spark-plug in the cylinder. The timing-wedge 46, as may be observed, is slidably fitted within the igniter and is forced

against the adjusting-timing-quadrant 47 by the action of the expansion spring 48. The timing-quadrant 47 is pivotally secured to the igniter at 49 and is provided with the graduated cam-sections 50 which sections offer a range of adjustment for the timing-wedge 46. The timing-wedge 46 may be positioned, through the manipulation of the timing-quadrant 47, to assume any position within the range provided by the cam sections of the quadrant.

The crank-shaft 2 is preferably provided with the spiral gear 51 which drives the gear 52, which rotates the gear 53 through the shaft 54 to which the gears 52 and 53 are secured. 55 represents the base-frame which is rigidly secured to the engine bed 1, as shown in Fig. 1, and forms the bearing for the shaft 54, as shown in Fig. 25, and the operating shaft 56 which carries the gear 57 and which gear is rigidly secured thereto. The shaft 56 is preferably provided with the pin 58 and is partly housed in the up-right-stand 59 which is preferably secured to the base-frame 55, as shown in Figs. 1 and 25. Secured to the up-right stand 59 is a threaded collar 60 which is preferably provided with the friction pins 61 shown in Figs. 7, 8 and 9. 62 represents the operating and gear-shifting screw which is coupled with, or made integral with the operating-wheel 63 to rotate therewith as shown in Fig. 7, and which freely permits the shaft 56 to rotate therein. The hand wheel 63 is provided with the coupling-end 64 which houses the coupling-collar 65 of the spiral-gear-sleeve-member 66, which slidably fits said shaft 56. Said spiral-gear-sleeve-member 66 is preferably provided with the spiral gear section 67, the upper bearing section 68, the lower bearing section 69, and the slots 70 in which the pin 58 of the shaft 56 slidably fits, as shown in Figs. 7 and 11. The upper section 68 of the spiral-sleeve-member 66 is provided with the coupling collar 71 which is secured thereto in any suitable manner, as by means of the pins 72 which permit the sleeve-member 66 to rotate within said collar 71 independent of the same, but, however, causes the collar 71 to travel axially with the sleeve-member as shown in Figs. 7 to 9 inclusive, and to which collar 71 is secured the main air-valve spindle 73. The coupling-collar 71 is preferably provided with the contact indicator springs 74 which are fixed to said collar 71 and project through the slot 75 provided therefor in the igniter-circuit-closing-member 76 which carries the slotted insulating panel 77 to which are secured the "forward" and "reverse" contact-members 78 and 79, respectively, which connect with the common binding post 80, as shown in Fig. 2, to which the ground wire 81 of the igniters 42 are preferably coupled. The ig-

4
niter-circuit-closing-member 76 is preferably supported on the upper spiral gear housing member 82, which in turn is supported on the lower gear housing member 83; said members when coupled together preferably form the bearings for the spiral-gear-sleeve-member 66 as well as house the timing-shaft-gear 84 which is secured to rotate with the timing-shaft 85, Fig. 8. The igniter-circuit-closing-member 76 supports the main-air-valve-casing 86 which is provided with the annular recess 87 having the outlet 88. The bore of said main air-valve casing 86 is preferably provided with the ported sleeve 89 which ports with the recess 87 through the ports 90, Fig. 10; said ported sleeve member 89 is held in position with said valve-casing 86 by means of the cap 91 through which 10

cap the compressed air from the compressed air system of the engine communicates with the valve 92, through the pipe 93 which is coupled with the compressed air-receiving-tank 94 and which tank is preferably supplied with compressed air by the compressor cylinder 13 through the pipe 95. The valve 92 fits within the ported cylinder member 89 and is adapted to slide within the same as indicated in the Figs. 7, 8 and 9, the valve being provided with the perforations 96 in the partition thereof, as shown in Fig. 10 for allowing the compressed air to flow through and into the lower end of the valve, as is necessary when the valve 92 is positioned as shown in Fig. 9.

The timing-shaft 85 (Fig. 1), which in the case of the type of engine shown in the drawings is timed to run at the same speed as the crank-shaft of the engine, is supported in suitable bearings 97 provided therefor, and may be provided with cams or cranks if desired for actuating the operating members of the auxiliary air-valves and igniters. In the drawings, however, the timing-shaft 85 is shown provided with the air-valve eccentrics 98, 99 and 100 for the cylinders 6, 7 and 8, respectively, and the igniter eccentrics 101, 102 and 103 for the ignition apparatus of the cylinders 6, 7 and 8, respectively; the air-valve-eccentrics 98, 99 and 100 being coupled with their respective auxiliary air-valves of the cylinders 6, 7 and 8 through the eccentric-rods 104, 105 and 106, respectively, while the igniter eccentrics 101, 102 and 103 are coupled with their respective igniters of the cylinders 6, 7 and 8 by the eccentric-rods 107, 108 and 109 respectively, Fig. 1.

In the drawing, as shown in Fig. 1, the timing-shaft 85 is coupled with the magneto 110 for driving the same, said magneto being provided (Fig. 3) with the contacts 111, 112 and 113 which connect with the spark-plugs 114, 115 and 116 operating in the cylinders 6, 7 and 8, respectively; 117, Fig. 3,

representing the rotary wiping contact of the magneto 110 shown in said Fig. 1; thus providing in Fig. 1 for the engine therein shown a double ignition system, namely, the igniter-system and the magneto-system, it being here understood that both systems may be coupled to operate simultaneously with the engine, or either one or the other of the two systems may be operated at any time independent of the other according as may be desired, also that the engine may be equipped with both systems or with either one of said systems alone if desired, or the engine may be equipped with an ordinary battery and timing system, in which case the timer may be operated by said timing-shaft 85 and thus be controlled by the within operating gear.

Having thus described the parts of my invention in detail, the manner in which the same may be employed is as follows:

First, it will be observed that in the "neutral" position of the operating-gear, as indicated in Fig. 7, the electric circuits for the igniters 42 as well as for the magneto 110, are "open" since the contact springs 74 for the igniter circuit are in the "neutral" position, as shown in Fig. 2, and are disengaged from the "forward" and "reverse" contact plates 78 and 79, respectively, and the rotatable wiping contact 117 of the magneto 110 is disengaged from the contact-members, as shown in Fig. 3; also the main air-valve 92 assumes the position in which no air can pass from the receiver 94 to the auxiliary air-valves of the engine, since the ports 90 are covered as shown in Fig. 7. The length of the ports 90 may be made to suit conditions, it being understood that the longer the same are made to extend beyond the "neutral" center thereof the earlier will be the period of opening of the valve; also, on the other hand the length of the valve 92 may be dimensioned to suit the required conditions in reference to the time of opening or closing of the valve.

The time of opening of said auxiliary air-valves (as indicated by the dotted circle marked "a" shown on the crank circle "c" Fig. 27) is preferably designed to be at a point about 5° beyond the head-dead-center position of the crank for the particular cylinder, and the time of closing of said valve is preferably designed to be as indicated in said Fig. 27 and Fig. 28 by the "full" circle 4, which is but a few degrees, as 7° for example, before the point of exhaust, which is preferably designed to be about 35° from the crank-end-dead-center position of the crank; thus the range of opening of the auxiliary air-valves for each cylinder occurs between the point about 5° beyond the head-dead-center of the crank for that cylinder to a point approximately 140° beyond said dead-center position as shown in Figs. 27 and 28. The sparking in the cylinders of the engine

is preferably timed to occur on the head-dead-center position of the crank for the particular cylinder, so that the auxiliary air-valve for each cylinder is allowed to open 5 5° after sparking occurs therein.

It will be here noted that when the operating-gear is set in the "neutral" position the main air supply is cut off and the electrical circuits are broken so that the engine 10 is inoperative.

With the cranks 3, 4 and 5 of the engine set as shown in Figs. 1, 25 and 26, wherein the arrow marked "F" represents the "forward" direction of rotation of the crank-shaft of the engine, while the arrow marked "R" represents the "reverse" direction of rotation of said crank-shaft, that since the middle cylinder 4 is on head-end-dead-center ready to go down on the firing stroke, that 15 in a three-cylinder engine it will be ready to assume that firing stroke whether the engine will turn in the direction of the arrow marked "F" or "R", but it becomes necessary, however, if desiring to operate the engine in the direction marked "F" to start the crank 3 in that direction so that the crank 4 will be carried beyond the head-dead-center position when the same will proceed on its firing stroke; while to operate 20 the engine in the "reverse" direction it is necessary to start the opposite crank 5 in the "reverse" direction so that the crank 4 will be carried beyond the head-dead-center position in that reverse direction when it will 25 proceed with its firing stroke.

Bearing that feature in mind, it will be observed in Fig. 26^a that when the engine comes to rest with the cranks set as shown in said figure, which represents the other 40 of the possible balancing and settling positions of the crank-shaft for a three-cylinder engine wherein one of said cranks is positioned in the crank-end-dead-center as against the head-end-dead-center shown in 45 Fig. 26, that for the "forward" running of the engine it will be necessary to start the crank "X" first, when the crank "Y" will follow and assume its firing stroke as it passes the head-dead-center position in that direction, or for "reverse" running of the engine it will be necessary to start crank "Y" in the "reverse" direction when crank "X" will follow on the working stroke when passing the head-dead-center position in 50 that "reverse" direction. Thus it will be observed that for a three-cylinder engine, or for engines in multiples of three, at all times the crank-shaft will position itself when the engine is at rest so that certain 55 of the cranks will carry the same in one direction for starting purposes, while others will take it in the "reverse" direction for starting purposes. A similar condition may be had in the case of a four-cylinder engine with cranks set 90° apart or with 60

engines having cylinders in multiples of four.

To start the engine in the "forward" direction, the engineer or operator manipulates the hand-wheel 63 so that the shifting screw 62 feeds downward, as shown in Fig. 8, when it will be observed that the spiral-gear-sleeve-member 66 is forced downward therewith, and in so doing causes the timing-shaft-gear 84, which meshes with the spiral gear 67, to be turned through an angular distance of approximately 90° , and thus results in advancingly shifting the eccentrics carried secured to said shaft from the positions indicated in the "neutral" diagrams 16, 17 and 18 to the positions indicated in the "full forward" corresponding diagrams 19, 20 and 21 advancing the eccentrics, as may be observed, say 90° from the "neutral" position in the forward running direction, 85 indicated by the arrow marked "f," of the timing-shaft 84.

With the shifting of the spiral-gear-member 66 downward, the contact members 74 are brought into engaging position with the forward contact plate 78, as indicated by the dotted positions shown in Fig. 2, and thus close the circuit for the igniters 42; and also the main valve 92 is shifted to a position wherein the ports 90 are free to 90 permit the passing of the compressed air from the compressed air system of the engine to enter into the distributing pipe 37 which discharges into the auxiliary valves of the engine.

As previously explained, for the "forward" running of the engine, it is necessary to start the crank 3 in the "F" direction, and it will be observed by referring to the diagram Figs. 16 and 19 which correspond to the cylinder 6 which is operated by the crank 3, that in shifting the timing-shaft 85 from the "neutral" position indicated in Fig. 16 to the "full forward" position indicated in Fig. 19, that the igniter eccentric 101 is first forced upward when the same engages with the armature of the igniter and disengages therefrom and causes the generation of the spark for that cylinder; and also that the auxiliary air-valve 105 38 for that cylinder opens to admit the air therethrough, as shown in Fig. 19 which positively forces the piston in said cylinder 6 downward, when immediately upon the starting of said crank 3 the igniter eccentric 102 for the cylinder 7 starts to travel upward as indicated in Fig. 20 and generates the spark in said cylinder 7, forcing the piston operating therein down on its working stroke. The left end cylinder 8 110 in the meantime is compressing, as shown in Fig. 21, when no sparking can be had from the igniter members thereof and when the valve 38 therefor is traveling upward and is closed as shown in said Fig. 21. 115 120 125 130

After the piston in said cylinder reaches the head-dead-center position, the performance of the previous cylinders will be duplicated therein, and so the engine will continue running in the "forward" direction, following the crank sequence 3, 4, 5, -3, 4, 5, etc.

In a similar manner the angular turning of the timing-shaft 85 caused by the shifting of the spiral-gear 67 through the manipulation of the hand-wheel 63, as hereinabove suggested, results in turning the rotatable wiping contact 117 of the magneto (Fig. 3) in the direction of the arrow marked "F" (Fig. 3), when the same makes contact with the contact member 111 which sparks the cylinder 6 operated by the crank 3 (the auxiliary air-valve for that cylinder operates exactly as has already been explained), so that both the ignition systems, namely, the igniter and the magneto systems, may operate simultaneously with reference to the sparking in the cylinders of the engine, and may be adjusted to spark the same cylinders at practically the same intervals. Thus it may be understood that both of said systems may be employed to operate simultaneously with the engine if desired, or that either one or the other of the two systems may be employed alone when the engine is equipped with both of them. Also, the engine may be equipped with but one of said ignition systems, it being understood that for smaller engines the ordinary battery and timing systems may be employed to good advantage (the magneto system being the most preferable however), while for larger types of engines although the high tension igniter system is the most preferred, it is commonly found that both the igniter and magneto are employed, one or the other serving as an auxiliary ignition system for the engine.

It will be here understood in starting the engine from cold, when there may not be any mixture in the cylinders to ignite, or when there is no compression in the cylinders, or when the engine does not ordinarily start on the spark for any other reason, that as soon as the operating-gear is manipulated to start the engine, the operating-gear-air-valve opens the main compressed air supply to the engine; therefore, the cylinder or cylinders having its crank or cranks lying in the "open range" of the auxiliary air-valves (as for example for "forward" running of the engine), the cylinder 6, which is operated by the crank 3, Figs. 1, 25 and 26, will be charged with compressed air from the compressed air system of the engine, the pressure of which may be appreciable, say 114.7 lbs. ab., whereupon the piston therein will be forced to start on its working stroke. Similarly, thereafter, if the following cylinder, as 7 which is operated by the crank 4,

does not ignite when the crank 4 comes into the "open range" of the auxiliary valve for that cylinder, the compressed air from the air system will enter therein and the piston thereof will also be forced to assume its working stroke, and so on, when the following crank 5 (which has been compressing) comes into the "open range" of the auxiliary air valve for its respective cylinder, if for any reason the same does not operate on its spark the compressed air from the air system will enter into it and force its piston to operate on its working stroke, and so on. Thus when the engine in such a case is turned over a few times on the air as suggested, it soon picks up on its own working medium and assumes its normal working functions, whereupon, in the case of an engine operating on my improved retarded combustion cycle, the auxiliary valves continue thereafter to first, admit compressed air for completing the combustion within the cylinders of the remaining unburnt carboniferous products of the initial mixtures, and then secondly, to stratify the burnt gases in the cylinders. In a similar manner the engine may be forced to start in the reverse direction by the medium of the compressed air when for any reason the spark fails to start the same. 95

It will also be understood that as soon as the crank-shaft of the engine is caused to rotate, that the shaft 56, which may be coupled therewith in any suitable manner, as for example, by means of the gearing shown in Fig. 25, is rotated therewith and will therefore continue to rotate the timing-shaft 85 which is driven thereby as long as the crank-shaft keeps rotating.

Now for causing the engine to operate in the "reverse" direction, the hand-wheel 63 is manipulated in the opposite direction to that for the "forward" running of the engine hereinabove explained, and therefore forces the spiral gear 67 to move upward, said gear 67 when the engine is at rest being limited to a sliding motion only, while when the engine is operating is both rotatable and slidabile, as may be understood from the manner in which the same is coupled with the other working parts of the operating-gear. This upward movement of the spiral gear 67 now causes the timing-shaft-gear 84 to be angularly shifted approximately 90° in the opposite direction to that shown in Fig. 8, so that the eccentricities for the different cylinders are shifted from the "neutral" positions indicated in the diagrammatic views 16, 17 and 18 to the "full reverse" diagrammatic views for the corresponding cylinders indicated in Figs. 22, 23 and 24, it being observed that the eccentricities for the "reverse" running of the engine are shifted and positioned just opposite to the positions shown in the "full" 130

forward" diagrams, namely, 19, 20 and 21, for the corresponding cylinders. Simultaneously with the shifting of the eccentrics from the "neutral" position to the "reverse" 5 position the indicator and contact springs 74 are this time brought into engagement with the reverse contact plate 79 and close the circuit for the igniters in exactly the same manner as was done when the gear 10 was shifted for the "forward" running of the engine. Also, the main air-valve 92 is this time shifted in the up-position as indicated in Fig. 9, when the bottom thereof unports the ports 90 and the compressed air 15 admitted into the valve from the compressed air system of the engine is permitted to pass through said ports and into the distributing-pipe 37 which communicates with the auxiliary air-valves 38 of the 20 engine. In this "reverse" manipulation of the operating gear it will be observed that the shifting of the operating eccentrics will cause a sparking to occur in cylinder 8 which corresponds to crank 5 Fig. 26 and 25 will also open the auxiliary air-valve 38 for that cylinder, as shown in Fig. 24, when the middle cylinder will immediately generate a spark on the head-dead-center position of the crank and 5° after passing the 30 same in the "reverse" direction when carried by the first operating crank 5 in the "reverse" direction will admit the air into the cylinder through the auxiliary air-valve 38 for that cylinder if necessary, and so on, 35 the sequence of operation of the cranks in the "reverse" direction being 5, 4, 3—5, 4, 3, etc., instead of 3, 4, 5, etc.

It will be here noted that an engine of the type herein shown, described as operating 40 on my improved retarded combustion cycle hereinabove mentioned, relies upon the introduction of a fuel constituent (as compressed air) during the working stroke of the piston for each cylinder for the purpose of supporting combustion to complete the combustion of the residual unburnt fuel constituents remaining for the initial mixture therein, and to further introduce compressed air, after completed combustion occurs, for stratifying the burnt gases in the combustion-chamber in the cylinders, continuing with said stratifying operation to a point just previous to the opening of the exhaust for the cylinder as is fully explained in my aforesaid application,—the self-starting function of the valve herein explained being but secondary to the two functions just mentioned, namely, the introducing of compressed air for completing combustion during a certain period of the working stroke of the cylinder, and then the stratifying the burnt gases of the cylinder with compressed air between the point of 50 said completed combustion and a point just previous to the reaching of the exhaust.

It will be observed that the automatic co-acting valves 29 of the auxiliary valves 38 will automatically open when the pressure of the compressed air passing through the valves 38 into the chambers 30 behind them exceeds the pressure within the combustion chambers of the cylinders in which the same operate, and will be seated, as shown in full in Fig. 30, when the pressure within the combustion chambers of the cylinders exceeds that of the air system behind them. It will also be observed that while the drawings show the operating-gear shifted from the "neutral" position to either the "full forward" or "full reverse" running positions of the engine, that the gear may be designed to offer a variable range between the "neutral" position indicated in Fig. 7 and the "full forward" position indicated in Fig. 8, or the "full reverse" position indicated in Fig. 9, it being understood that by raising or lowering the position of the operating hand-wheel 63 from the "neutral" position shown in Fig. 7, that all the operating members as the timing-shaft 85 which is angularly controlled by the positioning of said operating hand-wheel, will be relatively adjusted, according as the distance through which the operating hand-wheel 63 is moved for either the "forward" or "reverse" directions of operation of the engine, and will thus vary the performance of the mechanisms associated therewith and controlled thereby, and therefore, by properly positioning the hand-wheel 63 in the required position either one side or the other of the "neutral" position, according as to whether "forward" or "reverse" running of the engine is required, any range of speed for the engine may be had as desired, in either one direction or the other; and that the gear affords a simple and reliable means for positively varying the speed of the engine in either direction, or for shifting the engine from one direction of rotation to the other, producing thereby a flexible manipulating means for controlling and governing the working operations of an internal combustion engine, especially such as may be operating on my improved retarded combustion cycle hereinabove referred to and disclosed fully in my aforesaid application,—it being remembered, however, in that connection that the same operating-gear may be employed for operating valves used for purposes other than that for which the same are employed in connection with my improved retarded combustion cycle, and may also be employed with four cycle types of engines as well as two cycle engines, and I therefore do not wish to be limited to the specific application or embodiment of the invention as herein disclosed.

It may also be observed that while I show eccentrics operating the reciprocating types

of igniters and auxiliary airvalves, I do not wish to be limited against employing cams or cranks for actuating said mechanisms in place of the eccentrics as shown.

5 It may also be observed that as soon as the engine starts rotating the shaft 56 will rotate therewith and will carry the spiral-gear-sleeve-member 66 therewith, which will rotate the timing-shaft 85 through the gear 84, it being understood that the mere sliding action of the spiral-gear 67 without any rotation thereto will also cause the timing-gear 84 to rotate but through an angular distance, the spiral gear 67 when thus sliding serving 10 as a "rack," and when the spiral-gear 67 is once shifted to the set position as shown in either Figs. 8 or 9, that when the shaft 56 rotates the same will rotate therewith and in turn rotate the timing-gear 84 which 15 carries the timing-shaft 85 to which the same is secured, and will thus operate the ignition and air-mechanisms of the engine.

It will also be noted that while the spiral-gear-sleeve-member 66 has both the sliding 20 and rotatable action, as described, the coupling collar 71 is limited, however, to but the sliding action imparted thereto by the shifting of the operating-gear from the "neutral" position thereof; therefore, the 25 main air-timing-valve 92 which is coupled with said coupling member 71 is also limited to the sliding or reciprocating action which is imparted to said spiral-gear-sleeve-member 66 when the same is shifted to operate 30 the engine in either one of its working directions.

It will thus be observed that the invention affords a simple operating-gear for internal combustion engines which is equally 35 applicable, with little modification, to reversing as well as non-reversing engines, and provides a ready means for manipulating the engine so that the same will be flexible and variable in the working operations thereof, according as may be desired. The gear may be built horizontal or vertical, depending upon the type of engine with which the same is employed, and substantial according as the size of the engine requires; 40 and is applicable for small types of engines as well as large, being at all times absolutely reliable in its operation, simple in construction, and affords every advantage possible for ordinary gas engine work, especially so for manipulating the auxiliary 45 mechanisms required in an engine operating on my improved retarded combustion cycle.

Claims.

1. An operating gear of the character described for internal combustion engines operating on the retarded combustion cycle, comprising means for actuating the auxiliary valves thereof; means for operating said actuating means for said auxiliary 50 valves; means for varying the working op-

erations of said auxiliary valve actuating means; and means for holding said valve actuating varying means in set position with the engine; and means coöperating with the shifting means for opening the supply of the 70 medium to be transferred through said auxiliary valves.

2. An operating gear of the character described, for reversing internal combustion engines operating on the retarded combustion cycle, comprising means for actuating the auxiliary valves thereof; means for operating said actuating means; means for reversing said actuating means; means for regulating said actuating means; means for holding said regulating means in set position with the engine; and means connected with the actuating means for opening the supply of the medium to be transferred through said auxiliary valves. 85

3. An operating gear of the character described for internal combustion engines operating on the retarded combustion cycle, comprising means for actuating the auxiliary valves and the ignition apparatus 90 thereof; means for operating said actuating means for said auxiliary valves and said ignition apparatus; means for varying the time of operation of said auxiliary valves and ignition apparatus actuating means; 95 means for holding said varying timing means in set position; means for closing the ignition circuit for the engine; and means coöperating with the shifting means for opening the supply of the medium to be 100 transferred through said auxiliary valves.

4. An operating gear of the character described for reversing internal combustion engines operating on the retarded combustion cycle, comprising means for actuating the auxiliary valves and ignition apparatus 105 thereof; means for reversing said actuating means; means for regulating the timing of said actuating means in either of the operating directions thereof; means for holding 110 said regulating means in the required position; means for closing the ignition circuit for the engine; and means connected with the latter means for opening the supply of the medium to be transferred through said 115 auxiliary valves.

5. An operating gear of the character described comprising a main shaft adapted to be operated by the crank-shaft of the engine; a telescoping shaft provided with 120 a spiral-gear and adapted to slidably fit said main shaft for sliding purposes and to normally rotate therewith; a timing-shaft provided with a gear engaging with said spiral-gear and adapted to be angularly advanced 125 thereby by the sliding action thereof and to normally rotate therewith; means provided on said timing-shaft for actuating the valve mechanism and the ignition apparatus of the engine; means for slidably regulating and 130

setting said telescoping shaft; and means connected with the telescopic shaft for closing the circuit for said ignition apparatus.

6. An operating gear of the character described, comprising a main shaft adapted to be operated by the crank-shaft of the engine; a telescoping shaft provided with a spiral-gear and adapted to slidably fit said main shaft for sliding purposes and to normally rotate therewith; a timing-shaft provided with a gear engaging with said spiral-gear and adapted to be angularly advanced thereby by the sliding action thereof and to normally rotate therewith; means provided on said timing-shaft for actuating the auxiliary valve mechanism and the ignition apparatus of the engine; means for slidably regulating and setting said telescoping shaft; and means connected with the telescoping shaft for opening the main air supply to said auxiliary valve mechanism.

7. An operating gear of the character described, comprising a main shaft adapted to be operated by the crank-shaft of the engine; a telescoping shaft provided with a spiral-gear and adapted to slidably fit said main shaft for sliding purposes and to normally rotate therewith; a timing-shaft provided with a gear engaging with said spiral gear and adapted to be angularly advanced thereby by the sliding action thereof and to normally rotate therewith; means provided on said timing-shaft for actuating the auxiliary valve mechanism and the ignition apparatus of the engine; means for slidably regulating and setting said telescoping shaft; means connected with the latter for closing the circuit for said ignition apparatus; and means for opening the main air supply to said auxiliary valve mechanisms.

8. An operating gear of the character described, comprising a main shaft adapted to be operated by the crank-shaft of the engine; a telescoping shaft provided with a spiral-gear, adapted to slidably fit and slide on

said main shaft and to normally rotate with said main shaft; a timing-shaft operated by said spiral-gear of said telescoping member; means provided on said timing-shaft adapted to operate the ignition apparatus coupled with the engine; means coupled with said telescoping shaft adapted to axially operate therewith for closing the electric circuit for the ignition apparatus of the engine; means for shifting and setting said telescoping shaft in the required position with said operating gear; and means for supporting said means of said operating gear in working relationship with the engine.

9. An operating gear of the character described, comprising a main shaft adapted to be operated by the crank-shaft of the engine; a telescoping member, provided with a spiral-gear, adapted to slidably fit said main shaft, to axially move thereupon and to normally rotate therewith; a timing-shaft operated by said spiral-gear of said telescoping member; means provided on said timing-shaft adapted to operate the ignition apparatus and the auxiliary compressed air-valve mechanisms employed with said engine; means for shifting and setting said telescoping member for varying the angular setting of said timing-shaft; means coupled with said telescoping member adapted to open and close the ignition circuit of the engine; means coupled with said telescoping member adapted to open and to cut off the main compressed air supply of the engine; and means for supporting and coupling the aforesaid operating gear means in working relationship with the engine.

In testimony whereof I have signed my name to this specification in the presence of two subscribing witnesses.
